A. C. SHIMER,
VAPORIZING MANIFOLD,
APPLICATION FILED DEC. 6, 1916.

1,289,942.

Patented Dec. 31, 1918.

UNITED STATES PATENT OFFICE.

ALLEN C. SHIMER, OF ANDERSON, INDIANA, ASSIGNOR OF ONE-HALF TO FRANK L. TRACY, OF ANDERSON, INDIANA.

VAPORIZING-MANIFOLD.

1,289,942.

Specification of Letters Patent. Patented Dec. 31, 1918.

Application filed December 6, 1916. Serial No. 135,411.

To all whom it may concern:

Be it known that I, ALLEN C. SHIMER, a citizen of the United States, residing at Anderson, in the county of Madison and State 5 of Indiana, have invented a new and useful Vaporizing-Manifold, of which the following is a specification.

It is the object of my invention to facilitate the operation of internal combustion engines, by supplying the explosive mixture with a certain amount of moisture, most conveniently drawn from the radiator usually associated with the engine in automobile construction, heating this moisture to 10 prevent it from being carried into the engine in liquid form, also heating the complete supply of explosive mixture, preferably after the moisture has been added to it, and obtaining heat from the exhaust gases; 15 and doing this in a unitary structure formed as an intake manifold.

The accompanying drawing illustrates my invention. Figure 1 is a side elevation of an arrangement embodying my invention, 25 showing the manifolds and radiator in full lines and the associated engine in dotted lines; Fig. 2 is an elevation of the intake manifold and carburetor, showing some of the parts in section; and Fig. 3 is a section 30 on the line 3-3 of Fig. 2.

The engine 10 is indicated as a multi-cylinder engine, having a water-cooling system including a radiator 11. The engine 10 discharges through the exhaust manifold 35 12, and receives its supply of explosive mixture through my improved intake manifold 13.

This intake manifold 13 has a central vertical passageway 14 which opens at the top 40 into an intermediate part of a horizontal passageway 15, the ends of which are upturned and provided with outlet openings 16 by which the explosive mixture is supplied to the cylinders. The lower or intake 45 end of the vertical passageway 14 is shown as being curved to a horizontal, and is connected to any suitable carburetor 17. At the junction of the passageways 14 and 15, but spaced laterally from the junction point as 50 clear from Fig. 3, the intake manifold is provided with an annular pocket 18, closed by a removable cap 19, and in this pocket is located a coil of tubing 20 which forms an

intermediate part of a tube 21 leading from the radiator 11 just above the water level 22 55 therein into the vertical passageway 14, as clear from Fig. 2. Vapor rising from the water in the radiator 11 passes by this tube 21 and through the coil 20 into the intake passage 14 where it mixes with the carbureted air from the carburetor 17 and passes therewith to the engine cylinders. The manifold 13 is also provided with a heating chamber 23 which is located below the horizontal passageway 15 and surrounds the 60 vertical passageway 14, the pocket 18 being located at the side of this heating chamber. This heating chamber 23 has near the top 65 an intake opening which is connected by a pipe 24 to the exhaust manifold 12, so as to 70 receive part of the exhaust gases, the amount of such gases being controlled by any suitable valve, such as a screw valve 25 at the intake opening to the chamber 23; and has at the bottom a discharge opening which is 75 connected to a pipe 26 leading to any suitable point of exhaust.

In operation, the engine 10 draws in an explosive mixture through the carburetor 17 and vertical passageway 14 to the horizontal 80 passageway 15, where it divides to go to the several engine cylinders. The exhaust from the engine is through the exhaust manifold 12, and part of the exhaust gases is diverted from such manifold through 85 the pipe 24 and heating chamber 23. This diverted part of the exhaust gases heats the intake manifold, thereby heating the explosive mixture supplied from the carburetor 17 to the engine. It also heats the coil 20 90 in the pocket 18, which coil carries moisture from the radiator 11 to the passageway 14. The heating of this moisture by the exhaust gases in the heating chamber 23 causes it to be supplied to the explosive mixture in a 95 highly heated condition, ordinarily as steam, and prevents any water in a liquid state from being carried over from the radiator 11 into the intake passageway 14. The mixture of moisture with the explosive mixture 100 materially assists in the operation of the engine, in a manner now well-recognized, and by having this moisture in the form of steam or water vapor the beneficial effects 105 therefrom are greatly increased; and at the same time the heating of the complete mix-

ture supplied to the engine facilitates the operation of the latter.

I claim as my invention:

1. In combination, an internal combustion engine, a carbureter for supplying explosive mixture thereto, a radiator forming part of the water cooling system for said engine, a connection from the radiator above the water line to the intake of the engine, and
10 means for heating the moisture passing through such connection and for also heating the explosive mixture supplied from the carbureter to the engine, said heating means comprising a chamber located in proximity
15 to said connection and to the passageway for explosive mixture from the carbureter to the engine, which chamber is connected to receive exhaust gases from the engine.

2. A unitary intake manifold structure for internal combustion engines, having a 20 passageway for explosive mixture from the carbureter to the engine, a passageway for exhaust gases from the engine, and a pocket, 25 said passageway for exhaust gases being in proximity to both the passageway for explosive mixture and the pocket, in combination with tubing located in said pocket so as to be heated by said exhaust gases, said tubing being connected to receive moisture from the associated radiator and to discharge into said intake passageway.

In witness whereof, I have hereunto set my hand at Indianapolis, Indiana, this 23 day of November, A. D. one thousand nine hundred and sixteen.

ALLEN C. SHIMER.
